United States Patent Office

Des. 193,823
Patented Oct. 9, 1962

193,823

INDOOR METAL FIREPLACE

Walter B. Hamilton, Jr., 2443 Medford Court W.,
Fort Worth, Tex.

Filed May 10, 1962, Ser. No. 70,070

Term of patent 14 years

(Cl. D81—7)

FIG. 1

FIG. 2

FIG. 3

FIG. 1 is a front elevational view of an indoor metal fireplace, showing my new design;

FIG. 2 is a side elevational view thereof; and

FIG. 3 is a top plan view thereof.

I claim:

The ornamental design for an indoor metal fireplace, as shown.
